UNITED STATES PATENT OFFICE.

HENRY DIERKER, OF GLENFIELD, PENNSYLVANIA.

PRESSED-STEEL METAL BED-LOCK.

1,344,583.

Specification of Letters Patent. Patented June 22, 1920.

Application filed December 15, 1919. Serial No. 344,837.

To all whom it may concern:

Be it known that I, HENRY DIERKER, citizen of the United States, residing at Glenfield, in the county of Allegheny and State of Pennsylvania, have invented certain new and useful Improvements in Pressed-Steel Metal Bed-Locks; and I do hereby declare the following to be a full, clear, and exact description of the invention, such as will 10 enable others skilled in the art to which it appertains to make and use the same.

This invention relates to beds and particularly to a method of fastening a side bed rail to the bed post and to an improved 15 side rail.

An object of this invention is to provide a quick and easy means for attaching a side rail to a bed post and at the same time to affix the cross bar between the bed posts, and 20 also to provide a universal attachment which may be readily and quickly attached to all different makes of beds and bed posts, and also to provide a means for reversing a side rail and an improved reversible side rail.

25 With these and other objects in view the invention consists in the construction, the combination, the detail, and arrangement of parts as hereinafter more fully described and claimed.

30 In the drawings:

Figure 1 is a plan of the attachment at the bed post with the bed post in section.

Fig. 2 is a side elevation of Fig. 1 partly broken away.

35 Fig. 3 is a partial end elevation of Fig. 2.

Fig. 4 is a detail of the wedge B Fig. 1.

Fig. 5 is a view at right angles of Fig. 4.

In the embodiment of my invention I provide a pressed steel bracket A provided with 40 an arcuate surface 2 comating the contour of the usual bed post herein designated I, which bracket is perforated at 3 to admit of the insertion of a bolt through a like perforation in the bed post I and which when the 45 bolt J is clamped it will be obvious it will be rigidly affixed to the bed post. Affixed to bracket A is a cross angle beam K connecting this post thereby with the other post at the same end of the bed. The bracket A 50 is of angular form as viewed in Fig. 3 and provided with a channel side L to receive a bed rail N hereinafter described and also to receive a wedge D. This channel member is 55 preferably affixed to member A by electric welding after the member A has been pressed in shape. The channel member is

recessed at F and G to provide clearance for protruding portions from the cutaway angle iron N in whichever position it might rest, as for instance in an inverted position the clearance would be necessary at the respective 60 F and G recesses. Bed rail N comprises an angle iron which ordinarily is preferably an inch and one half by two inches by one eighth inch, the inch and one half side being 65 the transverse side. It is cut away at H leaving only the two inch side with a slight overhang for which clearance is provided at F and G. That is to say when the one and one half inch side is at the top most position then this overhang is cared for by the recess at G and when it is in the lowermost position it is cared for by the recess at F. There is also provided in the bracket A a 70 groove C to admit of a lug D on the wedge 75 B which tends to lock the wedge from shaking out. Wedge B is also provided with a lug E for a convenient means of hitting it with a hammer and driving it out. As best shown in Fig. 2 after the bracket A has been 80 affixed to the bed post all that is necessary in assembling the side rail is to insert it into the slot at L and to drive the wedge B in place.

Claims:

1. A bed comprising a pair of angle irons with one side of said irons cut away at each end, bed posts, brackets mounted on said bed posts, said brackets being open at the end opposed from the bed post into a recess 90 forming an inner contour substantially to the contour of the side of the said cutaway angle iron remaining as being cut away and provided with an additional recess arranged parallel with the first recess for receiving a 95 wedge for locking said rail.

2. A bracket for holding the connecting members for bed posts comprising a piece of sheet metal bent in contour conforming to said posts and provided with a horizontal 100 and vertical side between said post and the opposing post at the other end of the said bed, the vertical side being provided with a recess for receiving a flat bar portion of the said rail and also for receiving there beneath 105 a wedge for locking said bed rail in said bracket, and also provided with an auxiliary groove for receiving a lug from the wedge in locking said wedge in said bracket.

3. A bracket for holding the connecting 110 members for bed posts comprising a piece of sheet metal bent in contour conforming

to said posts and provided with a horizontal and vertical sides between said post and the opposing post at the other end of said bed, the vertical side being provided with a recess for receiving a flat bar portion of the said rail and also for receiving therebeneath a wedge for locking said bed rail in said bracket, and also provided with an auxiliary

groove for receiving a lug from the wedge in locking said wedge in said bracket, and a wedge, said wedge to be inserted beneath said bed rail in locking said bed rail in position and provided with a lug for engagement by hammer in knocking it outward.

In testimony whereof I affix my signature. 15
HENRY DIERKER.
